UNITED STATES PATENT OFFICE.

FRED A. GERLING, OF PORTLAND, OREGON,
DRAFT APPLIANCE.

No. 901,701.

Specification of Letters Patent. Patented Oct. 20, 1908.

Application filed March 6, 1907, Serial No. 360,855. Renewed March 27, 1908. Serial No. 423,590.

To all whom it may concern:

Be it known that I, FRED A. GERLING, a citizen of the United States, residing at Portland, in the county of Multnomah and State of Oregon, have invented a new and useful Draft Appliance, of which the following is a specification.

This invention relates to draft appliances for use in connection with traction engines in hauling harvesting or other machines or for operating plows and the like.

The object of the invention is to provide a draft appliance in which the point of application of the load may be adjusted in accordance with conditions, and the draft point changed so that the power of the engine may be utilized to the best advantage on different grades.

A further object of the invention is to provide a draft appliance which may be readily shifted vertically of the machine, and which will automatically engage the frame of the machine and become locked thereto with a degree of force proportionate to the weight of the load.

A further object of the invention is to provide a draft appliance in which the traction or propelling power will increase as the resistance increases; for instance, in plowing when the longitudinal pull on the draft appliance is partly upward, the plow will tend to hold the traction wheels down against the ground thus materially increasing the traction force.

A still further object of the invention is to generally improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a side elevation partly in section of a draft appliance constructed in accordance with my invention. Fig. 2 is a top plan view of the same. Fig. 3 is a sectional view of the forward connecting bar of the draft frame. Fig. 4 is a detail perspective view of one of the sliding sections or gripping blocks detached.

Similar numerals of reference indicate

corresponding parts in all of the figures of the drawings.

The apparatus forming the subject matter of the present invention is designed for use in connection with traction or other engines which are generally employed for moving agricultural machines, or for the hauling of logs or loads of different characters where draft animals are generally used and in the drawings there is shown a traction engine of the ordinary construction in which 5 designates the frame of the vehicle and 6 the traction wheels.

Depending from the opposite sides of the vehicle frame 5 and bolted or otherwise rigidly secured thereto are depending guide bars 7 having their lower ends secured in any suitable manner to diagonal braces 8 which extend longitudinally of the frame 5 and are rigidly secured thereto, as indicated at 9. The depending bars 7 which are preferably in the form of I-beams, are slightly inclined towards the forward end of the machine, as shown, and serve as guides for suitable gripping blocks 10, the latter being operatively connected with a traction frame, indicated as a whole at 11. The traction frame 11 is preferably rectangular in shape and formed of strong metallic tubes suitably connected by corner couplings 12 and reinforced by diagonal braces 13 which are connected with the center of the frame by a cross coupling 14. The transverse bar 15 forming the forward end of the traction frame is extended laterally beyond the adjacent couplings 12 and pivotally mounted at 16 to the gripping blocks 10. The rear tube or bar 17 of the traction frame is arranged to receive a two part clevis hitch 18 which may be adjusted in the direction of the length of the tube and locked in place by a suitable pin 19 that may be passed through any one of a number of openings 20 formed in said tube.

The clevis hitch is provided with a shank 21 for connection to the plow or other machine to be operated and by adjustment of the clevis and adjustment of the point of connection between the machine and the bar 17, the point of application of the load may be shifted laterally.

As a means for raising and lowering the forward end of the draft frame 11, there is provided a hand operated lever 22 secured to a transverse shaft 23 journaled on the frame of the vehicle and provided with a

5 minal crank arms 24 which are connected through the medium of links 25 to the laterally extending pivots or lugs 25' of the gripping blocks 10 whereby said blocks may be adjusted vertically of the frame thereby to vary the angle or inclination of the traction frame.

10 The couplings 12 at the rear end of the traction frame are provided with vertically disposed ears 26 between which is pivotally mounted a yoke 27, the latter being connected with the crank arm 28 of an operating lever 29 pivotally mounted on the frame of the vehicle and similar in construction to the 15 operating lever 22.

15 It will thus be seen that by operating the lever 29 the clevis 18 may be raised or lowered so as to change the points of application of the load while by operating the lever 22 the 20 inclination of the traction frame may be varied at will so as to throw the weight on any particular portion of the vehicle and thus increase or decrease its traction force.

25 The diagonal braces 8 are preferably reinforced and strengthened by substantially vertically disposed braces 30 having their opposite ends connected with the braces 8 and frame 5, respectively. It will thus be seen that when the traction frame is attached to the load and the vehicle started 30 the blocks 10 will grip the guide bars 7 and assist in locking said bars in adjusted position, the gripping force being proportioned to the resistance offered. It will also be 35 noted that by manipulating the levers 22 and 29 the opposite ends of the traction frame 10 may be raised or lowered either simultaneously or independently of each other and that the traction frame may be 40 supported at any angle or inclination with respect to the bed of the vehicle.

45 From the foregoing description it is thought that the construction and operation of the device will be readily understood by those skilled in the art and further description thereof is deemed unnecessary.

Having thus described the invention what is claimed is:

1. In draft mechanism, a vehicle, a traction frame, means operatively connected with the opposite ends of the traction frame for raising and lowering the same thereby to change the point of application of the load, and a coupling device carried by and adjustable transversely of the frame.

2. In draft mechanism, a vehicle, a traction frame, a coupling device carried by and adjustable transversely of the traction frame, and means operatively connected with the opposite ends of the frame for raising and lowering the same thereby to change the point of application of the load.

3. In draft mechanism, a vehicle, a traction frame, a coupling device adjustable laterally of the frame, levers operatively con-

nected with the opposite ends of said frame for raising or lowering either end thereof, and means for locking the coupling device in adjusted position.

4. In draft mechanism, a vehicle, a traction frame, levers mounted on the vehicle, links forming a pivotal connection between the levers and the traction frame thereby to tilt the latter at any angle with respect to the vehicle, and a coupling device secured to 75 and adjustable transversely of the frame.

5. In draft mechanism, a vehicle, a traction frame, levers mounted on the vehicle for independently raising and lowering the opposite ends of the frame, links forming a pivotal connection between the levers and the traction frame, and a coupling device secured to 80 and adjustable transversely of one end of the frame.

6. In draft mechanism, a vehicle, guides 85 depending from the vehicle, a traction device slidably mounted on the guides, an operating lever, links forming a pivotal connection between the operating lever and one end of the traction frame, and means for 90 raising and lowering the opposite ends of said frame.

7. In draft mechanism, a vehicle, guides depending from the vehicle, gripping blocks 95 slidably mounted on the guides, a traction frame pivotally connected with the gripping blocks, means for adjusting the gripping block longitudinally of the guide bars, and means for raising and lowering the rear end of the traction frame.

8. In draft mechanism, a vehicle, guide bars depending from the vehicle, gripping blocks slidably mounted on the guide bars and provided with laterally extending trunnions, a traction frame pivotally connected 105 with the gripping blocks, an operating lever carried by the vehicle, links forming a pivotal connection between the operating lever and the trunnions of the gripping blocks, and means for raising and lowering the rear 110 end of the traction frame.

9. In draft mechanism, a vehicle, a shaft extending transversely of the vehicle and provided with terminal crank arms, a traction frame, links forming a pivotal connection between the crank arms and one end of the traction frame, a lever for rocking the shaft thereby to raise and lower the forward end of the traction frame, and means for raising and lowering the opposite end of said 115 frame.

10. In draft mechanism, a vehicle, depending guides secured to the vehicle, gripping blocks slidably mounted on the guides, an operating lever, links forming a pivotal connection between the gripping blocks and lever, a yoke pivotally secured to the rear end of the traction frame, and a lever operatively connected with the yoke for raising and lowering the adjacent end of said frame, 125 130

thereby to change the point of application of the load.

11. In draft mechanism, a vehicle, a substantially rectangular traction frame consisting of transverse and longitudinal bars, reinforced by diagonal braces, a clevis adjustable laterally of the frame on the rear bar thereof, an operating lever operatively connected with the forward end of the traction frame for raising and lowering the same, and means for raising and lowering the rear end of said frame.

12. In draft mechanism, a vehicle, guide bars depending from the vehicle and terminating in diagonal braces for attachment to the vehicle frame, gripping blocks slidably mounted on the guide bars and provided with laterally extending trunnions, a traction frame pivotally connected with the

gripping blocks; an operating lever, links forming a pivotal connection between the operating lever and trunnions for raising and lowering one end of the traction frame, a clevis carried by the opposite end of the traction frame, a yoke pivotally associated with the clevis end of said frame, and an operating lever connected with the yoke for raising and lowering the adjacent end of the frame thereby to vary the point of application of the load.

In testimony that I claim the foregoing as my own, I have hereto affixed my signature in the presence of two witnesses.

FRED A. GERLING.
